AXLE CLEANING DEVICE

John R. McLaggan, Springfield, Mo.

Application April 11, 1952, Serial No. 281,806

6 Claims. (Cl. 15—88)

This invention relates to a machine for automatically cleaning elongated, generally cylindrical devices and more particularly to a machine for cleaning railroad car axles.

According to Government regulations, railroad car axles which have been removed must be magnetic particle tested before being remounted. Before such inspection can be made, it is, of course, necessary that the axle be thoroughly cleaned. This has been in the past a very tedious and relatively expensive operation, in view of the fact that the axles, after long periods of use on railroad cars, are caked with dirt, rust, scale and other foreign matter. Therefore, it has heretofore taken one or more men a considerable period of time to clean the axles so that they may be magnetic particle tested in accordance with the aforementioned regulations.

It is an object of this invention to provide a machine for automatically cleaning railroad car axles in a short period of time and in an extremely efficient and satisfactory manner.

It is a further object of this invention to provide a machine of the aforementioned type, which need not be operator attended and into which and from which axles can be automatically fed and discharged.

It is a still further object of this invention to provide a machine of the aforementioned type, which is relatively inexpensive to manufacture, easy to maintain and relatively compact in construction.

These and other objects of this invention will become apparent from the following detailed description, taken in conjunction with the accompanying drawings, in which:

Figure 1 is a front elevational view of the machine of this invention;

Fig. 2 is a view, partially in section and partially in elevation, taken along the line 2—2 of Fig. 1;

Fig. 3 is a top plan view of the structure illustrated in Fig. 1;

Fig. 4 is an end elevational view of the structure illustrated in Fig. 1;

Fig. 5 is a front elevational view of the structure illustrated in Fig. 4, taken in the direction of the arrow 5 thereon;

Fig. 6 is an enlarged sectional view of the structure illustrated in Fig. 1, taken along the line 6—6 thereof; and

Fig. 7 is a view similar to Fig. 6, illustrating the parts in a raised position.

Referring now to the drawings, it will be seen that the machine includes a stationary supporting structure 9. The supporting structure 9 includes a supporting member 11, on which a pair of side-by-side shafts 13 and 15 are rotatably supported by journal or bearing blocks and brackets 17. The shafts 13 and 15 extend laterally across the front of the machine and the left hand end of the shaft 13, as viewed in Fig. 1, is connected through a suitable coupling 19, with an electric motor 21, which rotatably drives the same. The shaft 13 is provided adjacent the coupling 19 with a gear 23, which is drivingly connected with an aligned gear 25 on shaft 15 by means of a chain 27, so that rotation of the shaft 13 causes rotation in the

same direction of the shaft 15. A pair of end to end spaced rollers 29 are provided on the shafts 13 and 15 adjacent the chain 27, and a similar pair of end to end spaced rollers 31 are provided adjacent the opposite end of the shafts 13 and 15. The rollers are spaced so as to properly receive, support and rotatably drive a railroad car axle 33 positioned thereon in a manner which will be hereinafter described. The opposite ends of the axle 33 rest on the rollers 29 and 31 and when the rollers are rotatably driven the engagement of the rollers with the axle will cause rotation of the axle. While the axle may rotate at any desired speed, it has been found that a speed of approximately 37 R. P. M. is satisfactory, and in order to provide rollers which will properly wear and properly rotate the axle, it has been found that a steel roller having a bronze rim operates satisfactorily.

Supported above the rollers 29 and 31 is a stationary track or frame member 35, which is supported adjacent its opposite ends by frame portions 37. A carriage or truck 39 is movably supported on the track member through rollers 41 for carrying a cleaning device or mechanism, generally indicated at 43, as can be best seen in Figs. 4 and 5. The carriage or truck 39 is adapted to be reciprocated laterally so as to carry the cleaning mechanism longitudinally of the axle 33 and clean the same from one end to the other. In order to reciprocate the carriage 39 an endless chain 45 extends around suitable pulleys 47 and 49, disposed adjacent opposite ends of the track member 35. A slack adjuster 51 is provided adjacent the right hand pulley 49 for adjusting slack in the chain in a conventional manner. The pulley 47 is connected to the output shaft 53 of an angle drive mechanism 55, the input shaft of which carries a gear 57. The gear 57 is connected with a gear 59 carried on the left hand end of the shaft 15, as viewed in Figs. 1 and 2, by means of a chain 61. The chain 45 is connected with the truck or carriage 39 in any suitable manner so that when the motor 21 is operated to cause rotation of the axle supporting rollers 29 and 31, the truck or carriage 39 will be reciprocated or moved along the track longitudinally of the axle.

In order to clean the axle 33 the cleaning device is illustrated as incorporating spaced rotary brush members 63 which engage the axle during its reciprocation and effectively clean all dirt, rust, scale and foreign matter therefrom. While rotary brushes are illustrated as providing the cleaning means, it will be appreciated that other cleaning mechanisms may be incorporated, such as a sand blasting mechanism or other suitable devices. The brushes 63 are supported on an axle or shaft 65, which in turn is journaled in the lower ends of a pair of interconnected spaced bracket or support members 67. The bracket or supporting members 67 are of a generally inverted L shape and include downwardly extending angular portions 69 and a generally horizontal or platform portion 71. Supported on the front of the horizontal portions 71 is a suitable electric motor 73, the drive shaft of which carries pulleys 75 which are connected with pulleys 77 on a shaft 79 supported by the bracket or supporting member 67 below the motor. Belts 81 connect the pulleys 75 and 77 so that the shaft 79 is rotatably driven by the motor 73. Pulleys 77 are carried by the shaft 79 between the bracket members 67 and are connected with pulleys 85 on the brush shaft 65 by belts 87. The brushes are therefore rotatably driven by the motor 73, through a suitable belt drive arrangement. While the brushes may rotate at any desired speed, it has been found that rotation of the brushes at a speed of around 2500 R. P. M. produces satisfactory results.

The horizontal portions 71 of the bracket members 67 are provided with a downwardly extending ear or projection 89, which projection is pivotally connected to the carriage 39 by a hinge or pivot pin 91. Due to the fact that the motor 73 is disposed forwardly of the hinge pin

91, as well as the brushes 63 on the lower end of the bracket member 67, the brushes will be normally retained in engagement with the axle supported by the rollers 29 and 31. However, when the axle 33 is moved forwardly out of engagement with the rollers 29 and 31 and onto a downwardly inclined track 93, as can be seen in Fig. 4, the brushes will be swung upwardly out of the way by the forward movement of the axle, about the pivot pin 91. As soon as the axle has passed under the brushes 63 the brushes will swing down into engagement with the next axle supported by the rollers. A cushioning piston and cylinder unit 94 is provided for cushioning the downward movement of the brushes and preventing damage to the same. Thus the brushes can swing out of interfering relationship with axles which are being discharged from the machine, but will be gravity returned into proper engagement with the next axle to be cleaned. Supported on the bracket members 67 is a cross member 95 having abutments 97 on the opposite ends thereof, which are adapted to engage and actuate limit switches 99 or 101 supported on the track member 35 adjacent the opposite ends thereof. Upon actuation of either of the limit switches 99 or 101, the direction of rotation of the motor 21 will be reversed so that not only will the axle be rotated in the opposite direction, but the direction of movement of the carriage and cleaning mechanism will be reversed. The switches are so located that only the portions of the axles between the wheel bearing or journal portions, on the opposite ends of the axles, are cleaned. The bearing or journal portions must be re-turned so there is no necessity of cleaning the same. It is possible to satisfactorily clean an axle with one pass of the brushes thereover in one direction, but if desired, or found necessary two passes of the brushes can be made in the cleaning operation wherein the axle will be rotated in two directions and the brushes, while being rotated, will be moved in opposite directions across the axle to clean the same.

In the particular embodiment illustrated in Fig. 1 of the drawing, the carriage moves first from right to left, strikes the limit switch 99, and then moves from left to right. During the return stroke of the carriage and cleaning mechanism and just prior to the actuation of the limit switch 101, a projecting arm or abutment 105 on the cleaning mechanism strikes a lever 107, or some other suitable actuating device or mechanism, supported by the stationary framework adjacent the limit switch 101. The lever 107 is normally held in the position illustrated in Fig. 1 by a spring 109, but when the carriage is moving to the right the abutment 105 strikes the lever 107 and moves the same in a clockwise direction before striking the limit switch 101. The actuation of the lever 107 causes actuation of an air cylinder unit 111 of any suitable design or construction supported on the stationary framework 9 adjacent the right hand edge of the machine, as viewed in Fig. 1. The actuation of the lever 107 causes the air in the cylinder unit 111 to force the piston thereof downwardly and thus move the piston rod 113, which is connected with the piston in any suitable manner, in a downward direction. The movement of the piston rod 113 causes movement of a mechanism to be described, which ejects the axle 33, supported by the rollers 29 and 31, away from the rollers and sends it down the track 93. Simultaneously a subsequent axle to be cleaned, numbered 115 in Fig. 4, is moved into engagement with the rollers 29 and 31. Therefore, the subsequent axle to be cleaned is moved into its position on the rollers 29 and 31 just before or simultaneously with the actuation of the limit switch 101, so that when the carriage starts its movement from right to left the next axle to be cleaned will be in the proper position and the previously cleaned axle will have been ejected from the machine. It will of course be obvious that if the axles are to be cleaned with only one pass of the brushes, a lever or other suitable mechanism, must be provided adjacent

limit switch 99 so as to actuate air cylinder unit 111 when the brushes approach switch 99, as well as switch 101, as illustrated.

In order to maintain the machine in continuous automatic operation, a plurality of axles to be cleaned are placed on an inclined track 117 which terminates at an inclined supporting structure 119 on the back of the machine, which supporting structure is provided with a notched or cut out portion 121 for receiving and supporting the next or subsequent axle to be cleaned, as soon as the axle supported on the rollers has been ejected. Therefore, with this arrangement a continuous supply of axles may be provided and the machine will automatically feed the same into the cleaning position and eject the clean axle from the machine. The ejecting and feeding mechanism illustrated in the drawing comprises a crank or lever 122, which is disposed in an inclined position with the forward end thereof connected to the lower end of the piston rod 113 in any suitable manner, so that when the piston rod moves downwardly a laterally extending shaft 123, to which the back or lower end of the crank 122 is rigidly connected, will be rotated in a clockwise direction, as viewed in Fig. 4.

Supported on the shaft 123 at laterally spaced points 25 are linkage structures 125, each of which includes a generally horizontal link 127 and a vertical link 129 interconnected or joined at 131. The upper end of each of the link portions 129 is pivotally connected to the under side of a platform 133, which is pivotally supported at its front end on a pivot pin 135. Projecting upwardly from each platform 133 below the axle 33, supported by the rollers, is a finger 137 which is provided with a spurlike portion 139 on the back end thereof. A second finger 141 projects upwardly from each platform member 133, below the framework notch or recess 121, for supporting the next axle to be cleaned, and has its top edge forwardly and downwardly inclined, for a reason which will herein-after appear. When the piston rod 113 is moved downwardly due to actuation of the lever 107, the linkage 40 mechanisms comprising members 122, shaft 123, and members 127 and 129, are actuated so that the links 129 move upwardly against the under side of the platforms 133. The front end of each platform pivots above its pivot pin 135 as the back end is swung upwardly so that, as can be seen in Fig. 7, the axle 33 supported by the rollers is lifted upwardly by the finger 137 and moved forwardly onto the inclined track portion 93 and out of engagement with the rollers 29 and 31. At the same time the finger 141 moves upwardly and engages the subsequent 45 axle or next axle to be cleaned 115, and raises the same out of its supporting notch 121, and due to its inclined upper surface, moves the same forwardly along the supporting tracklike structure into engagement with the rollers 29 and 31. While the axle 33 which has been moved by the finger 137 will normally roll down the trackway and out of the machine, if for any reason it should tend to hang, the oncoming rolling axle 115 will knock the cleaned axle forwardly and out of the way. The axle 115 then assumes the position in engagement 50 with the rollers 29 and 31, the limit switch 101 is actuated by the cleaning mechanism, the brushes 63 which had been moved upwardly by the cleaned axle passing from the machine have dropped down by gravity, back into engagement with the new axle, and the carriage moves to begin the subsequent and next cleaning cycle. It will thus be seen that the axles are automatically fed 55 into the machine, ejected from the machine, and cleaned while in the machine, without the necessity of an operator being present. Furthermore, if the machine is operated at the speeds previously described, an axle can be cleaned even with the reciprocating stroke in one minute and ten seconds. This cleaning time, in comparison with cleaning times previously found necessary for the cleaning of railroad axles, is extremely small, and a great saving in time as well as manpower is achieved through the 60

provision of the relatively simple, compact, durable, and inexpensive mechanism of this invention.

What is claimed is:

1. A machine for cleaning axles including stationary supporting structure, means on said stationary supporting structure for supporting and rotating an axle to be cleaned, means on said stationary supporting structure adjacent said supporting and rotating means for supporting a second axle to be cleaned, a device movably supported adjacent said supporting and rotating means for carrying means to engage and clean the axle during its rotation, means for moving said device longitudinally of the axle so that the axle will be cleaned from one predetermined point to another, means supported on said stationary supporting structure adjacent said axle supporting and rotating means actuatable to engage the axle and move the same away from said supporting means after the axle has been cleaned, means supported on said stationary supporting structure adjacent said second axle supporting means actuatable to engage the second axle and move the same into engagement with said axle supporting and rotating means, after the one axle has been cleaned, and means supported on said stationary supporting structure and operatively connected with both of said axle engaging and moving means actuatable by said device at the end of its movement during the cleaning operation to cause the actuation of both said axle engaging and moving means.

2. A machine for cleaning axles, including a stationary supporting structure, means rotatably supported on said stationary structure for supporting and rotating an axle to be cleaned, means for rotating said axle supporting and rotating means, track means supported on said stationary supporting structure adjacent said axle supporting and rotating means extending longitudinally of the axle, a carriage movably supported on said track means for movement longitudinally of the axle, a mechanism for carrying means to engage and clean the axle during its rotation, said mechanism being pivotally supported on said carriage so as to be movable toward and away from the axle to be cleaned, means supported on said stationary supporting structure adjacent said axle supporting and rotating means actuatable to engage the axle and move the same away from said supporting means after it has been cleaned, and means supported on said stationary supporting structure and operatively connected with said axle engaging and moving means actuatable by said mechanism at the end of its movement during the cleaning operation to cause the actuation of said axle engaging and moving means.

3. A machine for cleaning axles, including a stationary supporting structure, means rotatably supported on said stationary structure for supporting and rotating an axle to be cleaned, means for rotating said supporting means, track means supported on said stationary structure above said axle supporting means and extending longitudinally of the axle, a carriage movably supported on said track means, brush means engageable with said axle for cleaning the same, means rotatably supporting said brush means, including bracket members having a generally horizontal portion and a portion extending angularly downwardly therefrom in the lower end of which said brush means are supported, motor means supported on said horizontal portion, means operatively connecting said motor means with said brush means for rotatably driving the same, means pivotally connecting said bracket means to said carriage means so that said brush means can be moved toward and away from the axle supporting means, means supported adjacent said axle supporting means actuatable to engage the axle and move the same away from said supporting means after it has been cleaned, which movement will cause the brush means and its supporting structure to pivot away from said axle supporting means when the axle moves therefrom, and means supported on said stationary supporting structure

and operatively connected with said axle engaging and moving means and actuatable at the end of the movement of said carriage and brush supporting means during the cleaning operation of the axle to cause the actuation of said axle engaging and moving means.

5 4. A machine for cleaning axles including a stationary supporting structure, a pair of rollers disposed in an end-to-end spaced relationship and rotatably supported on said stationary supporting structure, a second pair of end-to-end spaced rollers rotatably supported on said stationary structure in spaced and aligned relationship with said first pair of rollers, said rollers being engageable with an axle to be cleaned to rotatably support the same, means for simultaneously driving said rollers to cause rotation of said axle while supporting the same, means movably supported on said stationary structure adjacent said rollers for cleaning the axle during its rotation, means for moving said cleaning means longitudinally between said spaced pairs of rollers so as to clean the axle, and means actuatable at the end of the movement of said cleaning means for engaging the axle and moving the same out of engagement with the rollers, said actuatable means including a first element disposed in the path of movement of said cleaning means and a second element operatively connected with said first element and movable upon engagement of said first element with said cleaning means to move an axle out of engagement with the rollers.

30 5. A machine for cleaning axles including a stationary supporting structure, spaced roller means rotatably supported on said supporting structure for engaging and rotatably supporting an axle to be cleaned, a device for cleaning an axle supported by said roller means, carriage means movably supporting said cleaning device on said supporting structure for movement longitudinally of the axle to be cleaned, motor means for rotating said roller means and for reciprocating said cleaning device carriage means, means connecting said motor means with said roller means, means connecting said motor means with said carriage means for causing reciprocation thereof, spaced switch elements supported on said stationary structure in spaced relation to each other and adapted to be engaged by said cleaning device when the latter approaches the end of its movement in either direction, said switch elements being operatively connected with said motor means so that when either of said switch elements is engaged said motor means will reverse the direction of movement of said roller means and said carriage means.

40 6. A machine for cleaning axles including a stationary supporting structure, spaced roller means rotatably supported on said supporting structure for engaging and rotatably supporting an axle to be cleaned, a device for cleaning an axle supported by said roller means, carriage means movably supporting said cleaning device on said supporting structure for movement longitudinally of the axle to be cleaned, motor means for rotating said roller means and for reciprocating said cleaning device carriage means, means connecting said motor means with said roller means, means connecting said motor means with said carriage means for causing reciprocation thereof, spaced switch elements supported on said stationary structure in spaced relation to each other and adapted to be engaged by said cleaning device when the latter approaches the end of its movement in either direction, said switch elements being operatively connected with said motor means so that when either of said switch elements is engaged said motor means will reverse the direction of movement of said roller means and said carriage means, means for engaging the axle supported by said roller means and moving the same out of engagement therewith upon actuation, and a contact element disposed in the path of movement of said cleaning device and engageable thereby prior to the engagement of the cleaning

device with at least one of said switch elements, to cause actuation of said axle engaging and moving means and the ensuing removal of said axle.
